UNITED STATES PATENT OFFICE

JAMES H. BRADFORD, OF TOOKE, UTAH, ASSIGNOR TO COMBINED METALS REDUCTION COMPANY, OF STOCKTON, UTAH, A CORPORATION OF UTAH

FROTH BREAKING APPARATUS

Application filed January 25, 1930. Serial No. 423,362.

Various industrial processes produce a large amount of froth or foam, and the principal object of the present invention is to devise simple, efficient and rapid means for breaking down the bubbles in the froth and to do this efficiently and completely with a minimum expenditure of energy.

The invention consists principally in flexible or flexibly mounted switches depending from a rotatably mounted arm in such a position as to be dragged through or across the froth bubbles. It also consists in the parts and in the arrangements and combinations of parts hereinafter described and claimed.

In the accompanying drawing, wherein like reference numerals refer to like parts wherever they occur,

Fig. 1 is a vertical cross-section of an agitation tank, chamber or container, equipped with an agitator and a froth breaking device conforming to the present invention,

Fig. 2 is a detail view showing a modified form of froth breaking device; and

Fig. 3 is also a detail view showing a modified form of froth breaking device.

In the construction illustrated in Fig. 1, an agitation or stirring or mixing tank 1 such as an ore treatment tank of standard design, contains liquid or pulp 2 and a removable cover 3, and with a propeller type agitator 4 suspended on a vertical shaft 5 in the middle of the tank 1. The shaft 5 passes through the cover 3, and is supported by suitable bearings 6 and 7, and is driven by a pulley 8, which in turn is driven by a belt 9.

The switch froth breaker comprises a horizontal arm 10 whose length is shorter than the internal diameter of the tank 1 and which is clamped at its middle to the shaft 5. Flexible switches 11 are attached to the arm 10 at their upper ends so as to hang downwardly. The arm 10 is clamped to the shaft 5 at such a distance from the liquid or pulp 2 that the lower ends of the flexible switches 11 are slightly above the liquid or pulp 2 when the shaft 5 is revolving, as shown in the drawing.

The arm 10 with the switches 11 thereon, rotates with the shaft 5 along with the pro-

peller agitator 4; the switches cutting through any froth that may form on the surface of the liquid or pulp 2. To prevent swirling of the liquid in the tank 1, it is desirable to place a baffle 12 across the tank or any suitable baffles in the tank below the level of the liquid or pulp 2.

Preferably the breaker arm is adjustable up and down, either on its revolving shaft, or by raising or lowering the shaft. While the shaft is shown as depending into the tank through the cover thereof, it is obvious that it may be mounted below said tank and extend upwardly through the bottom thereof, or the shaft may be inclined as in the case of portable direct connected agitators that are fastened to the top edge of the container and project therein at an angle.

In the modified form shown in Fig. 2, if desired, in order to enable more surface of the flexible material to come into contact with the froth, the lower ends of the flexible switches 11 are connected by flexible strips 13.

The construction shown in Fig. 3 shows members 14, either flexible or stiff, the upper ends of which contain hooks 15 which engage clamps 16 that are secured into the arm 10. Thus the switches are flexibly mounted.

It is noted that this apparatus can be used with any type of agitator or froth producing arrangement. Similarly a separate shaft can be used in connection with a pneumatic agitator, where no mechanical agitation is used, or where frothing results from chemical or other causes.

The device constituting this construction may rotate in an opposite direction to the agitator, or in highly swirling liquids may be stationary. It may also be used in open or closed containers, and if desired, the switches may be made hollow to permit introduction of gases, liquids, or other materials into the mixer or container. Also the switches as shown in Fig. 3 are flexibly mounted, which may be preferable in some instances over the flexible switch securely fixed at its upper end, as shown in Fig. 1.

The switch tail froth breaker is simple in

construction, is efficient, consumes very little power and if operated at the proper speed in relation to that of the liquid positively disintegrates froth and prevents its upward passage at a trifling cost and thus permits mixing of froth making materials and also makes possible simple methods of mixing chemicals or other materials which heretofore have required special and in some cases complicated and expensive apparatus. An additional advantage is its portability.

What I claim is:

1. Froth breaking apparatus comprising a rotatable shaft, an arm secured thereto which rotates with said shaft, and elongated flexible switches depending from said arm.

2. Froth breaking apparatus comprising a vertically disposed rotatable shaft, an arm extending laterally from said shaft and elongated flexible switches depending from said arm.

3. Froth breaking apparatus comprising a vertically disposed rotatable shaft, an arm extending laterally from said shaft and flexibly mounted elongated members depending from said arm.

4. The combination with a liquid container of a vertically disposed member therein, an arm extending laterally from said member and flexibly mounted elongated members depending from said arm and means for effecting relative movement between the depending members and the liquid.

5. The combination with a liquid container of a vertically disposed rotatable shaft therein, an arm extending laterally from said shaft, and elongated flexible switches depending from said arm to about the normal liquid level thereof.

40 6. The combination with a liquid container of a vertically disposed member therein, an arm extending laterally from said member and elongated flexible switches depending from said arm to about the normal liquid level thereof.

50 7. The combination with a container of a rotatable shaft therein, an arm extending from said shaft and elongated flexible switches depending from said arm whereby they cut through any froth that may form on the surface of the liquid.

55 8. Froth breaking apparatus comprising a container, a vertically disposed rotatable shaft therein, a lateral arm mounted on said shaft above the normal liquid level thereof and flexible switches depending from said arm whereby they cut through any froth that may form on the surface of the liquid.

60 9. The combination with a container of a vertically disposed rotatable shaft therein, an arm extending laterally from said shaft and elongated flexible switches, the upper ends of which are attached to said arm and 65 hang in vertical position to about the normal

liquid level thereof and whose lower ends are connected with flexible strips.

10. Froth breaking apparatus comprising a container, a vertically disposed rotatable shaft therein, an agitator member mounted on said shaft in the lower portion of said container, a lateral arm mounted on said shaft above the normal liquid level thereof, and flexible switches depending from said arm whereby they cut through any froth that may form on the surface of the liquid.

11. Froth breaking apparatus comprising a container, appropriate baffles below the normal liquid level, a vertically disposed rotatable shaft therein, an agitator member mounted on said shaft, a lateral arm mounted on said shaft above the normal liquid level thereof, and flexible switches depending from said arm whereby they cut through any froth that may form on the surface of the liquid.

Signed at Stockton, Utah, this 23d day of December, 1929.

JAMES H. BRADFORD.
